(57) **CLAIM**

The ornamental design for a handbag, as shown and described.

DESCRIPTION

FIG. 1 is a front isometric view of the handbag of the present invention;

FIG. 2 is second isometric view thereof;

FIG. 3 is bottom isometric view thereof;

FIG. 4 is a rear view thereof;

FIG. 5 is a front view thereof;

FIG. 6 is a right-side view thereof;

FIG. 7 is a left-side view thereof;

FIG. 8 is a top plan view thereof; and,

FIG. 9 is a bottom plan view thereof.

The broken lines shown represent stitching and form part of the claimed design. The dot-dashed broken lines represent boundaries to disclaim the interior of the handbag. The stippling in the figures is intended to show a contrast in color, texture and/or material, such that areas of the design shown with a stipple fill can be comprised of a different color, texture, and/or material than the non-stipple filled areas.
